WOVEN FABRIC

Edward P. Lord, Norwich, Conn.

Application July 14, 1939, Serial No. 284,565

1 Claim. (Cl. 139—420)

This invention relates to a woven decorative fabric.

A woven decorative fabric in accordance with this invention is of the tape, strap, or ribbon-like type and is designed primarily for use in tying packages to enhance the appearance of the latter and for ornamenting wrapped or unwrapped objects, but it is to be understood that the fabric, in accordance with this invention, is to be used for any purpose and in any connection for which it may be found applicable.

The invention resides in the production of a decorative fabric of the type referred to having a composite central portion or section and a pair of outer portions or sections, said central portion or section including a reinforced paper strip and said outer portions or sections being formed of closely related threads with a tinsel or lustrous effect.

The invention further aims to provide, in a manner as hereinafter set forth, a decorative fabric including an ornamented central portion or section and a pair of outer portions or sections, the ornamentation for the central portion or section being provided by printing or stamping the design or ornamentation on the outer surface of the paper strip, and the said side portions or sections being in the form of closely related continuous metallic strands having a tensile or lustrous effect connected with said central portion.

The invention further resides in the production of a woven decorative fabric of the type referred to having a flat thin composite central portion or section and a pair of flat thin outer portions or sections, the said central portion being formed of reinforced paper having a design superimposed on its outer surface, and the said outer portions or sections being in the form of closely related threads of the tinsel type.

The invention further resides in the production of a woven fabric of the type referred to including an ornamented reinforced paper center and flat groups of the desired width, formed of closely related parallels of tinsel threads connected at their inner sides with and corresponding in length to the sides of said center.

The invention further resides in the production of a decorative fabric of the type referred to which is strong, durable, conveniently handled for any use for which it may be intended, of a construction to arrest the transverse tearing thereof during application and when applied, having a distinctive and novel appearance, ap-

pealing to the eye, and produced at a comparatively low cost.

Embodying the aims aforesaid and others which may hereinafter appear, the woven decorative fabric consists of the novel construction, combination and arrangement of parts as will be more specifically described and illustrated in the accompanying drawing wherein is shown embodiments of the invention, but it is to be understood that changes, variations and modifications may be had with respect to the strip and with respect to the manner of producing it which falls within the scope of the invention as claimed.

In the drawing:

15 Figure 1 is a fragmentary view in top plan of the woven decorative fabric in accordance with this invention.

16 Figure 2 is a transverse sectional view upon an enlarged scale on line 2—2, Figure 1.

20 Figure 3 is a longitudinal sectional view upon an enlarged scale on line 3—3, Figure 1.

25 Figure 4 is an enlarged fragmentary exploded view in top plan of the structure shown by Figure 1, and

26 Figure 5 is a fragmentary view illustrating a modified form of the central part or inner section for the fabric looking towards one side edge of such part or section.

30 With reference to the drawing the fabric includes a central part or inner section of strip-like form which may be flat or corrugated. A flat central part or inner section is indicated at 1, Figure 1. A corrugated central part or inner section is indicated at 2, Figure 5. The central part or inner section of the fabric will be of the width and length desired.

35 The fabric includes the central part or inner section 1 or 2, a weft 3 constituting a retainer for the central part and a pair of outer sections 4, 5. The central part 1 or 2 will be hereinafter referred to in the description as an inner section and in the claim as a relatively wide flat central warp member of strip-like form. The retainer 3 is common to the web and said outer sections.

40 45 The inner section 1 consists of a thin continuous flat body 6 formed from a strip of paper stock of the desired thickness, width and length reinforced lengthwise thereof by spaced cotton threads 7 embedded therein. The cotton threads 50 7 preferably will be continuous and correspond in length to the length of body 6. The outer surface 8 of the body 6 has printed or stamped thereon throughout a suitable design, as indicated at 9. The body 6 preferably will be suitably colored. The reinforcing of the body 6 re-

duces the transverse tearing thereof to a minimum.

The weft 3 will be formed from a length of cotton thread 10 bent in a manner to provide outwardly arranged spaced inclined stretches 11, inwardly arranged spaced inclined stretches 12 extending at an opposite inclination with respect to the inclination of the stretches 11, bends 13 connecting the outer stretches 11 to the inner stretches, and bends 14 connecting the inner stretches to the outer stretches. The stretches 11 constitute what may be termed the front of the weft, the stretches 12 the back of the weft and the bends 13, 14 the sides of the weft. The length of weft 3 is to correspond substantially to the length of the body 6 of inner section 4. The latter is to be positioned between the outer and inner stretches of the weft 3. The width of body 6 is materially less than the length of the inner and outer stretches of the weft 3 and when positioned relative to the weft, the latter will have portions 15, 16 of the inner and outer stretches of weft 3 extended laterally in opposite directions from the sides of said body 6. There is associated with the weft 3 a pair of holder members 17, 18 in the form of continuous threads. The member 17 is arranged against the inner faces of the bends 13. The member 18 is arranged against the inner faces of the bends 14. The members 17, 18 act to hold the bends 13 in uniform spaced relation to the bends 14 whereby the stretches 11 and 12 will be of uniform length. The bends 13 are staggered with respect to the bends 14. The weft 3 also constitutes what may be termed a connector for coupling the outer sections 4, 5 against the opposite sides of the body 6.

The outer section 4 consists of a series of closely related continuous elements 19 in the form of threads, parts or strands, and which may be termed warp members. The elements 19 are interlaced or woven with and throughout the portion 15 of the weft 3 between one side of body 6 and the holder member 17. The latter is in the form of a warp member. The other outer section 5 consists of a series of closely related continuous elements 20 in the form of wires and which may be termed warp members. The elements 20 are interlaced or woven with and throughout the portion 16 of the weft 3 between 50 the other side of the body 6 and the member 18. The latter is in the form of a warp member. The interlacing or weaving of the elements 19, 20 with the weft portions 15, 16 contract parts of such portions and to provide the weft 3 with 55 what may be termed an open central portion which snugly encompasses the body 6. The interlacing of the elements 19, 20 with the weft portions 15, 16 connects the sections of the fabric together and further maintains the outer sec- 60

tions of the fabric in juxtaposition to the sides of body 6.

As before stated, the outer sections are in the form of threads, parts or strands and which may be cotton, linen, "Rayon" or rubber, but preferably the elements 19 and 20 of the outer sections will be formed from silvered copper wire to have a durable tinsel or lustrous effect. This statement also applies to the weft thread 3.

10 The modified form of decorative fabric, in accordance with this invention, and as shown by Figure 5, will be of the same construction as the fabric shown by Figures 1 to 4, with this exception that the inner section 2 will be corrugated throughout.

15 The bends or picks 13 of the weft 3 are relatively widely spaced apart. This statement applies to the bends 14.

20 The manner of forming the decorative fabric, in accordance with this invention, consists in first producing a relatively wide flat reinforced paper strip, decorating the outer face of the strip by printing or stamping thereon the desired ornamentations, then interlacing, by weaving the weft 25 3 relative to the warps indicated at 5, 17, 18, 19, 20, with the warp 5 arranged centrally of the fabric between the inner ones of the warps of the series 19, 20, and with the warps 17, 18 disposed outwardly of the entire warps of the two series 19, 20 and engaging the bends or picks 13, 14 of weft 3.

30 If the outer sections of the fabric are formed from warps consisting of copper wire, the latter is flattened, then silvered and wound onto spools and from the spools the wire is utilized in forming the said outer sections. The warps 17, 18 are connected to the outer sections and the outer sections connected to the inner section by the weft 3 and which is accomplished by weaving on what is well known as a "Sauer" loom.

35 It is to be understood that the paper body or central warp member 6 may be reinforced by cotton fibre in lieu of cotton threads.

40 What I claim is:

A woven decorated fabric of tape-like form comprising a central warp member formed of a relatively wide imperforate strip of paper having embedded therein, lengthwise thereof spaced parallel continuous threads constituting reinforcing means therefor and having its outer face provided with impressed means constituting a decoration for said face, two series of parallel lustrous warp threads each arranged at a side of the central warp member, and a weft interwoven with all of the said warp members with the picks of the weft relative widely spaced apart, said strip being transversely corrugated throughout.

EDWARD P. LORD.
